BARK REMOVING MACHINE

Clarence F. Knight, McGrann, Pa.

Application July 20, 1942, Serial No. 451,613

3 Claims. (Cl. 144—208)

My invention relates to the removal of bark from pulp wood logs and the like, and has among its objects and advantages the provision of an improved machine for removing bark from such logs.

In the accompanying drawings:

Figure 1 is a side elevational view partly in section of a machine in accordance with my invention;

Figure 2 is a view taken from the position indicated by line 2—2 of Figure 1;

Figure 3 is a view taken from the position indicated by line 3—3 of Figure 1; and

Figure 4 is a perspective view of a bark removing knife.

In the embodiment selected for illustration, I make use of a base 10 upon which is mounted two frame members 12 and 14, as by bolts 16. A bearing 18 is mounted on the base 10 for supporting a drive shaft 20 having a pinion 22 secured thereto. This pinion meshes with a gear 24 keyed to a shaft 26 rotatably supported in the frame members 12 and 14. Gear 24 is in mesh with a pinion 28 secured to a shaft 30 rotatably journaled in the frame members 12 and 14. To the opposite end of the shaft 30 is connected a pulley 32 for driving a belt 34 passing around a pulley 36 of considerably smaller diameter, which pulley is secured to a shaft 38 also rotatably journaled in the frame members 12 and 14. Upon the shaft 38 is secured a body 40, see Figure 3, which carries knives 42 for removing bark from the log 44 of Figure 1, which log is passed through the machine in right angular relationship to the shaft 38.

The body 40 is square in cross section and the knives 42 are secured to the body by screws 43 extending through openings 45 in the knives and threaded into the body 40. Each blade has a cutting edge 47 arranged at an angle of about twenty degrees to the back edge 49, this edge being arranged in parallelism with the axis of the shaft 38. The blades taper gradually from their angular leading edge 51 to their back edge 49.

A gear 46 is rotatably mounted on the shaft 38 and restrained from axial movement thereon by reason of its engagement with the knife-carrying body 40 and a collar 48 secured to the shaft by a setscrew 50. The collar 48 lies in engagement with the frame member 12. The log 44 is pressed against one face of the gear 46, and this gear is driven by a pinion 52 secured to the shaft 26. On the shaft 26 is mounted a disk 54 having one face thereof engageable with

the log 44 diametrically opposite the gear 46. The disk 54 is keyed at 56 for rotation as a unit with the shaft 26 but free to move longitudinally of the shaft. One end of the shaft 26 is rotatably supported in a bearing sleeve 58 having screw threads 60 coacting with the internal thread formation 62 of a bushing 64 secured in a bore 66 in the frame member 14.

Upon the shaft 26 is mounted a compression spring 68 having one end engaging a washer 70 pressed against the hub 72 of the disk 54 and its other end engaging a washer 74 engaging one end of the bearing sleeve 58. Thus the disk 54 is yieldingly pressed against the log 44, and the tension of the spring 68 may be adjusted through rotation of the bearing sleeve 58, the latter being provided with a handwheel 76 to facilitate such rotation.

In operation, the pinion 52 is considerably smaller than the gear 46 so as to rotate the latter at half the speed of the disk 54. The gear 46 and the disk 54 rotate in opposite directions with the result that rotary motion is imparted to the log 44 to bring the bark into engagement with the knives 42 as the log 44 moves longitudinally and rotatably through the machine. The knives 42 are rotated at a sufficiently high speed to perform an efficient cutting action on the log. Positive engagement between the log and the gear 46 and the disk 54 is assured by reason of the compression spring 68. Thus the resilient backing for the disk 54 compensates for variable log sizes and irregularities therein.

The longitudinal travel of the log through the machine is caused by the slippage on the slower turning member. The blades are tapered so that as the log rotates the whole of its circumference will come in contact with the cutting edges as the log progresses longitudinally across the blades.

The frame members 12 and 14 are braced at their upper ends by a brace rod 78.

Without further elaboration, the foregoing will so fully illustrate my invention, that others may, by applying current knowledge, readily adapt the same for use under various conditions of service.

I claim:

1. A machine of the kind described, comprising a plurality of rotary shafts spaced from each other, a cutter rotated by one of the shafts and disposed crosswise of a log when operated upon by said cutter, a displaceable disk on another of the shafts, and disposed longitudinally of the log and engaging the log at one side at a point substantially aligned with the transverse axis of

the log for imparting turning movement thereto, a gear loose on the cutter shaft and contacting the log on the side diametrically opposed to the side thereof contacted by the disk for longitudinally advancing the said log, a spring urging the disk toward the log, and a pinion carried by the shaft carrying the disk and of less size than the gear and meshing with the gear for driving the latter at less speed than the disk.

2. A machine of the kind described, comprising a plurality of rotary shafts spaced from each other, a cutter rotated by one of the shafts and disposed crosswise of a log when operated upon by said cutter, a displaceable disk on another of the shafts, and disposed longitudinally of the log and engaging the log on one side at a point substantially aligned with the transverse axis of the log for imparting turning movement thereto, a gear loose on the cutter shaft and contacting the log on the side diametrically opposed to the side thereof contacted by the disk for longitudinally advancing the said log, a spring urging the disk toward the log, a pinion carried by the shaft carrying the disk and of less size than the gear and meshing with the gear for driving the latter

at less speed than the disk, a drive shaft and connections between the drive shaft and the shaft carrying the cutter.

3. A machine of the kind described comprising a plurality of rotary shafts spaced from each other, a cutter rotated by one of the shafts and disposed crosswise of a log when operated upon by said cutter, a displaceable disk on another of the shafts, and disposed longitudinally of the log and engaging the log on one side at a point substantially aligned with the transverse axis of the log for imparting turning movement thereto, a gear loose on the cutter shaft and contacting the log on the side diametrically opposed to the side thereof contacted by the disk for longitudinally advancing the said log, a spring urging the disk toward the log, a pinion carried by the shaft carrying the disk and of less size than the gear and meshing with the gear for driving the latter at less speed than the disk, a drive shaft, and connections between the drive shaft and the shaft carrying the cutter, and means for increasing and decreasing the tension of the spring on the disk.
